WOOL PRESS

Francis Claude McNamara, Wentworthville, near Sydney, New South Wales, Australia, assignor to Sunbeam Corporation, a corporation of Illinois

Application October 1, 1945, Serial No. 620,386
In Australia August 22, 1944

1 Claim. (Cl. 100—12)

1 This invention relates to presses for wool and the like whereby the latter may be compressed into bales in a rectangular box-like body by means of a compressing head or monkey to which downward pressure is applied by mechanical means.

In presses of this type various means have been adopted so that in the upward position of the monkey, the latter may be moved sideways to give free access to the body of the press when placing the wool in the body prior to each compressing operation, but such known constructions do not give easy access or are usually provided with pressure applying means comprising a system of pulleys and a cable wound upon a winch drum, the cable being required to be slackened before swinging the monkey clear of the body. Furthermore, the cables owing to such slackness often require to be replaced upon the usual pulleys before a further compressing movement of the monkey can be made.

An object of the present invention is to provide improved pressure applying means for a press which will permit, in a box body type of press, free access to the body for loading and one which is free from the above disadvantages, is simple and quick in operation, and is not costly to manufacture compared with the more complicated types of presses already upon the market.

The present invention in common with most wool presses of this type has a box-like body with sides, front and rear, capable of being opened out when it is desired to withdraw the compressed bale from the body. The box-like body rests upon a base board and is open at the top.

Above the open top a monkey or compressor is mounted upon a vertical member and is forced down upon the wool by a system of pulleys, and a cable capable of being wound upon a winch drum.

The monkey is rotatably mounted upon the lower end of the vertical member and the latter is slidably in a crosshead which may be mounted upon two vertical supports disposed close to the respective sides of the body, the supports being preferably relatively movable with respect to the sides. The object in rotatably mounting the monkey with respect to the vertical member is to enable the monkey to assume a position in ac-

cordance with any slight irregularity in the packing of the wool into the press body during the filling operation. It will be appreciated that the monkey and the vertical member are capable of movement relatively to the crosshead.

2 According to the present invention, the crosshead, which extends across the top of the body of the press, is attached to the upper end of the said vertical supports, and may consist of two members between which the vertical member carrying the monkey is freely movable, in an up and down manner, but the said crosshead may be made in one piece if provision is made for the vertical member to move vertically in relation thereto when power is applied to the said member.

The means for applying power to the vertical member and the monkey carried thereby, comprises a system of pulleys and a cable, capable of being wound upon a suitable winch drum. The system of pulleys may be varied slightly but it consists essentially of two pulley wheels mounted centrally at the upper end of the vertical member, one above the other, and a pulley wheel carried upon the crosshead, near one end thereof. The arrangement of the pulleys is such that when a downward pull is exerted upon the vertical member the thrust is taken upon the crosshead at a point as near the vertical supports as is practicable. The cable for applying the downward pressure to the vertical member is anchored at one end, passes over the lower pulley wheel of the vertical member, round the pulley wheel on the crosshead, over the second pulley wheel on the said member and thence to a winding drum round which it is coiled when the drum is turned.

In order that the invention may be more readily understood reference will now be made to the accompanying drawings wherein:

Figure 1 is a front elevation of a press having pressure applying means in accordance with the present invention.

Figure 2 is a side view thereof.

Figure 3 is a detail view of part of the rear of the press on an enlarged scale, illustrating the means for applying downward pressure to the monkey and for raising the latter clear of the top of the body.

Figure 4 is a plan view, of the construction illustrated in Figure 1.

The body illustrated is of box-like formation, having a base 16, sides 10 and 11, front 12 and rear 13, held together by long pins 14 passed through strappings 15 of angle iron which overlap at the corners. The respective sides, front and rear, 10 to 13, inclusive, are supported upon a base 16 and the front 12 and side 11 are capable of being opened out about the pins 14 to remove the bale after moving the press locking clamp bracket 9 to the unlocked position. The press locking clamp bracket 9 as is best shown in Figs. 1 and 2 of the drawings comprises a vertical bar pivotally mounted to the angle brackets 15 on one side of the press body and adapted to slip over the ends of the angle brackets 15 on the front of the press body. When this locking clamp 9 is pivoted by swinging it to the left of the position shown in Fig. 1 of the drawings, the angle irons 15 on the front as viewed in Fig. 1 are free so that the front of the press body may be pivoted about the pin 14 to open the body for removal of the bale.

The top of the box-like body is open to receive the material to be compressed and above the open top a monkey 17 is positioned in such manner that it may be moved up and down, as desired, with relation to the body.

The press is provided with a crosshead 18 supported above the top of the body and through the said crosshead a vertical member 19 is capable of being moved by the means provided for applying downward pressure to the monkey 17, said monkey 17 being pivotally mounted as indicated at 44 upon the lower end of the said vertical member 19.

As illustrated the crosshead 18 is formed in two parts, see Figure 4, between which the member 19 carrying the monkey 17 is received in such manner that it may slide freely. At each end, the crosshead is secured to supports such as 20. The detailed construction of the supports 20 which are pivoted to the base 16 by pivot pin 48 which are disclosed in my co-pending application, Serial No. 620,385 filed concurrently with the instant application. To retain the supports 20 in the operative position shown in the drawings there are provided catches 41 fastened to the press body and having notched out portions for receiving therein the latching ends of the respective pawls 42 pivotally mounted on arms 43 which in turn are supported on the supports 20. The pawls 42 are capable of being withdrawn from the catches 41 by tie rods 45 which may be lifted by crank arms 47 defined on the respective ends of a transverse rod 48 having a crank handle 49. The crank handle 49 is also used to pull the cross head 18 and monkey 17 clear of the body of the press when the box-like body is made ready to receive therein material to be compressed. As best shown in Figs. 2 and 4 of the drawings, a pair of somewhat U-shaped guide brackets 50 are provided with one leg of each of the U's bolted to an associated one of the angle irons 15 and the other legs connected to the associated latches 41. These brackets are adapted to receive and support in the bight of the U the supports 20 when the crosshead and monkey assembly are to be supported clear of the press opening to allow wool to be placed in the said body. At one end of the crosshead a winch 21 is mounted and at the other end there is a pulley 22 and freely mounted. The vertical member 19 at or near its upper end has two pulleys 23 and 24

freely mounted one below the other. A cable 25 for applying a downward force to the monkey 17 is secured at one end to the crosshead 18 by means of a shackle pin 26 which is bolted to the said crosshead 18. After leaving the shackle 26, the cable 25 passes over the lower pulley 23, then round the crosshead pulley 22, over the upper pulley 24, on the vertical member 19, and is secured to the drum of the winch 21 in known manner.

The winch 21 has a ratchet wheel 27 capable of being engaged by an operating handle 28, which is bifurcated and carried upon the shaft 29 of the winch 21. The handle 28 has a suitable ratchet face or pin, not shown, for engaging the teeth of the ratchet wheel 27 in a conventional manner well understood by those skilled in the art. A crank handle 30 is mounted upon the shaft 29 to enable the winch 21 to be turned independently of the handle 28; a ratchet pawl 38 is also provided.

A pawl 31 is pivoted to the crosshead 18 and is adapted to engage a ratchet plate 32 set into the vertical member 19 for the purpose of safely retaining the said member in its elevated position above the body of the press until it is desired that the monkey 17 be lowered.

For the purpose of raising the monkey after pressure has been applied by the winch 21, cable 25 and system of pulleys 22, 23 and 24, a second winch 33 having a crank handle 34 is mounted upon the crosshead 18 and receives a cable 35 which passes beneath a pulley 36 freely mounted upon the lower end of the vertical member 19 just above the monkey 17, said cable 35 being secured to the crosshead by a pin 37 about which the pawl 31 is also pivoted.

The pulley arrangement upon the vertical member 19 and the crosshead 18 is such that the thrust on the said crosshead is widely distributed and that applied to the monkey is directly vertical.

When raising the monkey 17 by means of the second winch drum 33 it is necessary to see that the main winch drum 21 is free to rotate in an anti-clockwise direction as viewed in Fig. 3 of the drawings.

While there has been shown and described a particular embodiment of the present invention it will be apparent to those skilled in the art that various changes and modifications can be made without departing from the invention in its broader aspects, and it is therefore aimed in the appended claim to cover all such changes and modifications as fall within the true spirit and scope of the invention.

I claim:

In a press for wool or the like comprising a rectangular box-like body and a vertically movable monkey insertable into the open upper end of said box-like body and serving as a ram to compress material inserted into said body, a cross head supported on and above said body, a vertical member slidably mounted relative to said cross head, means for pivotally connecting the monkey to the lower end of said member, and a cable and pulley system for applying a downward thrust to said monkey comprising a freely rotatable pulley mounted at one end of said cross head, a winch mounted at the other end of said cross head, a pair of pulleys rotatably mounted adjacent the upper end of said vertical member one below the other, and a cable having one end secured to one end of said cross head and passing in succession over the lower pulley on said vertical member, then over said pulley at said one end of said

2,482,681

5

cross head, then over the upper pulley on said vertical member and into engagement with said winch, said cable and pulley system being applied entirely to and carried by said cross head and vertical member whereby operation of said winch causes downward movement of said monkey.

FRANCIS CLAUDE McNAMARA.
